UNITED STATES PATENT OFFICE.

HENRY WIESE, OF ANDERSON, INDIANA.

AIRPLANE.

Application filed September 28, 1926. Serial No. 138,205.

This invention relates to means for causing and controlling vertical movement of an air plane, whereby it can ascend and descend vertically instead of in the present substantially horizontal movement.

The problem of constructing air planes so that they can rise or descend vertically without difficulty has had its solution attempted by many inventors. The desirability of an upward starting off and a vertical landing is well recognized and the problem will have to be solved before air planes can come into general use, because it will be impractical to provide landing places suitably located or in sufficient numbers to meet the requirements of the users of air planes, if a large field is necessary for that purpose.

The use of a horizontal propeller, especially when located above the air plane, to tend to vertically lift the air plane, has been heretofore suggested and tried, but apparently without any success, as it has not yet come into practical use. One of the difficulties is the insufficient lifting power of the horizontal propeller of practical dimensions, and another trouble is that it will not cause the air plane to ascend or descend vertically, as the air plane will wobble and rock to an impractical and dangerous extent, as there is nothing to balance the air plane.

One feature of this invention consists in providing a substantially vertical air chamber under the horizontal lifting propeller with the upper end of the air chamber open to receive downwardly moving air from the propeller and with the lower portion of the air chamber curved so that it has an upward discharge against a horizontal baffle plate secured to the body of the air plane, whereby it will have a lifting effect that will aid the propeller in elevating the plane.

Another feature of the invention consists in providing two such air chambers, one on each side of the body of the plane with their lower ends discharging against said horizontal baffle plate. This is a very important feature because it balances and steadies the air plane in its vertical movement, whether ascending or descending, and prevents the sidewise or swaying movement of the air plane while ascending or descending.

Another feature of the invention consists in providing a double vertical air chamber on each side of the body of the air plane, one being the primary air chamber with downwardly moving current, above mentioned,

and the other a secondary air chamber for a return vertical movement of a portion of the air coming from the discharge end of the primary discharge chamber and providing a number of horizontal baffle plates on the side of the body of the air plane against which the upwardly moving current of air in the secondary air chamber impinges and also aids in the lifting movement of the air plane.

The full nature of the invention will be understood from the accompanying drawings and the following description and claims:

In the drawings, Figure 1 is a substantially central vertical section through an air plane, equipped with this invention, parts being omitted for the sake of clearness. Fig. 2 is a plan view of said air plane with parts broken away. Fig. 3 is a horizontal section on the line 3—3 of Fig. 1. Fig. 4 is a horizontal section on the line 4—4 of Fig. 1.

Some of the usual details of an air plane are not necessary to be shown or described herein, but in order to illustrate the general nature of this invention there is shown an air plane body 10 with wings 11 and a front propeller 12 for the forward movement of the air plane.

This invention consists in adding to such an air plane a horizontal propeller 15 mounted above the body 10 of the air plane on a vertical shaft 16 that is driven by an engine 17. The details of the means for driving this propeller are not set forth as they are immaterial, and in fact this feature of the invention is not by itself new theoretically, although so far as I am aware the horizontal lifting propeller has not been used in practice. On the underside of the body of the air plane there is rigidly secured a main long wide horizontal baffle plate 17^a, as seen in Fig. 1. Surrounding this baffle plate 17^a and enfolding the body 10 of the air plane, a system of air chambers or conduits is provided immediately below the horizontal propeller 15.

At each side of the body of the air plane there is what may be termed a primary air chamber 20 with a flaring open upper end located beneath the propeller to receive the air driven downward by the propeller. These primary air chambers have an outer side and lower end wall 21, and an inner wall 22 or partition 22. The walls 21 and 22 are parallel and extend longitudinally of the

air plane and parallel with the body thereof, as seen in Figs. 2, 3 and 4, and the lateral width of the primary air chamber 20 is relatively narrow and substantially uniform excepting at the flaring upper end, as shown in Fig. 1, and said chamber has considerable length parallel with the body of the air plane, as shown in Figs. 3 and 4.

Therefore, each of said chambers has considerable capacity and vertically they have the peculiar shape shown in Fig. 1, that is, after leaving the flaring upper end the chamber 20 curves downwardly and outwardly for some distance and then downwardly and inwardly and finally upwardly and inwardly to the discharge end which is located slightly below the main baffle plate 17^a. Hence, the downward current of air through said chambers 20 makes no sharp turn at any point, but travels in relatively slow curves so as to facilitate the movement of the air therethrough and not check the same and also to reduce and minimize the downward thrust of the air column. The theory of the action resulting from this construction is that a considerable and rapidly moving column of air will be driven down by the propeller into each of said primary air chambers, and the two air columns discharge with considerable force against the baffle plate 17^a and thus tend to force the air plane upward. The air discharged by said primary air chambers against the baffle plate 17^a escapes through the opening 23 beneath the discharge ends of said air chambers and the openings 24 from said discharge ends into the secondary air chambers 25.

The secondary air chambers 25 lie between the inner walls 22 of the primary air chambers 20 and the body 10 of the air plane and their air inlets are at their lower ends through the openings 24 and their outlet is at the upper end under and near the center of the propeller 15, as seen in Fig. 1. The chambers 25 have the same length as the chambers 20, see Figs. 3 and 4, but their width varies considerably as at the lower portion they are very wide, as seen in Fig. 1, while they are contracted as they extend upward.

There are a number of horizontal baffle plates 26 secured to the outer side wall of the body, as seen in Fig. 1, and extending into the chambers 25. The wall 10 of the body constitutes the inner wall of each chamber 25 excepting towards the lower end where there is a partition plate 27 extending from the body to the lateral edge of the main baffle plate 17^a. The theory of the air action in chambers 25 is that a portion of the air discharged from the discharge ends of the primary air chambers 20 escapes into the chambers 25 and travels upward with considerable speed and in such move-

ment impinges against the baffle plates 26 and tends to aid in lifting the air plane, on the same theory that the baffle plate 17^a and the columns of air in the primary air chambers 20 aid in the uplift of the air plane.

The air chambers above explained have another function in addition to the uplifting function above stated. The additional function is to balance the air plane in its vertical movement, whether in the upward or downward movement. Without the air chamber system explained, the air plane would sway widely in various directions, while ascending or descending because of the irregular air support of the propeller and there would be nothing to resist said swaying movement excepting gravity. The air chambers tend to resist lateral movement or sway of the plane.

While there is disclosed herein what is considered to be the preferable form of the arrangement of the air chambers, the invention is not limited to the particular form and arrangement shown, excepting that the chambers must be in a position to receive the downward air thrust from the propeller 15 and there must be a pair of them, one on each side of the center of the air plane, and in order to get the uplift, the air from the chamber must be discharged against the under side of one or more baffle plates secured to the air plane.

In the construction herein shown the main air chambers are the primary chambers 20. The secondary chambers 25 are desirable, but not necessary. While only one engine 17 is shown, and that rather diagrammatically, the engine construction can be varied. Preferably there should be one engine for the travelling propeller 12 and a separate engine for the lifting and descending propeller 15, as the lifting propeller will not be used after the desired elevation is reached so as to clear the houses, tree tops and hills and permit the main propeller 12 to cause the travel of the air plane. In such instance the engine driving the lifting propeller would be stopped. However, one source of power could be used to drive both propellers or either of them by using the proper clutch mechanism for stopping and starting either or both of the propellers.

The invention claimed is:

1. The combination with an airplane having a body, of a horizontal propeller central above the body of the plane tending to lift and control the vertical movement thereof, a horizontal baffle plate secured centrally on the underside of the body of the plane, and an air chamber on each lateral side of the body of the air plane having an upper inlet opening under said propeller for receiving the downward thrust of the air therefrom and at its lower end curved up-

wardly under and towards said baffle plate for discharging the air passing therethrough upwardly against said baffle plate, whereby the air currents through said chambers will 5 tend to lift the body of the air plane and resist swaying movement of the air plane while rising or descending.

2. The combination with an air plane having a body, of a horizontal propeller 10 above the body of the plane tending to lift and control the vertical movement of the plane, a horizontal baffle plate secured to the plane, a similar air chamber secured at each side of the body of the plane with 15 the upper ends thereof flaring and open below the propeller to receive the thrust of the air therefrom and the lower portion of said air chambers being curved to discharge upwardly against said baffle plate, substantially as set forth.

3. An air plane construction substantially as set forth in claim 2 with said baffle plate secured to the underside of the body of the air plane and with air escape openings between the discharge ends of said air chambers and the baffle plate, substantially as 25 set forth.

4. The combination with an air plane having a body, of a horizontal propeller above

the body of the plane tending to lift and 30 control the vertical movement of the plane, a horizontal main baffle plate secured to the underside of the body of the plane, a primary air chamber secured at each side of the body of the plane and having a flaring 35 upper end located immediately below the propeller to receive the downward thrust of air therefrom, and said air chamber extending downward and at its lower end curved so as to discharge upwardly under and 40 against said baffle plate, a secondary air chamber between each of said primary air chambers and the body of the plane in position to receive a portion of the air discharged by said primary air chambers 45 against said main baffle plate and with the secondary air chambers open at their upper end beneath the propeller so that a column of air will pass upwardly therethrough, and horizontal baffle plates secured to the side 50 of the body of the propeller and projecting into said secondary air chamber to receive the impact of the air passing upwardly therethrough, substantially as set forth.

In witness whereof, I have hereunto affixed my signature.

HENRY WIESE.
